Des. 207,474
Patented Apr. 18, 1967

207,474

TIRE PATCH

Virgil G. Erickson, Sunland, Calif., assignor to Tru-Flex
Rubber Products Company, Los Angeles, Calif., a cor-
poration of California

Filed July 25, 1966, Ser. No. 3,205

Term of patent 14 years

(Cl. D90—20)

FIG. 1.

FIG. 2.

FIG. 3.

FIG. 4.

FIG. 5.

FIG. 1 is a top plan view of a tire patch showing my new design;

FIG. 2 is a lower side elevation of the view in FIG. 1, the upper side being a mirror image thereof;

FIG. 3 is a left end elevation of the view in FIG. 1;

FIG. 4 is an enlarged transverse sectional view, taken substantially on line 4—4 of FIG. 1; and

FIG. 5 is an enlarged fragmentary longitudinal sectional view, taken substantially on line 5—5 of FIG. 1.

I claim:

The ornamental design for a tire patch, as shown.
